UNITED STATES PATENT OFFICE

REGINALD F. PETERS AND GLENN L. DAVIS, OF SPRINGFIELD, MISSOURI

GRINDING MACHINE

Application filed June 26, 1928. Serial No. 288,516.

This invention relates to a grinding machine designed primarily for use in connection with the grinding of angle cocks, but it is to be understood that a machine in accordance with this invention may be employed for any purposes for which it is found applicable, and the invention has for its object to provide, in a manner as hereinafter set forth, a machine of the class referred to so constructed and arranged for producing a uniform product and to meet the need of greater production at less cost.

A further object of the invention is to provide, in a manner as hereinafter set forth a machine of the character referred to for simultaneously grinding a plurality of angle cocks and further for selectively discontinuing the grinding action upon one of the angle cocks without discontinuing the grinding action upon the others.

A further object of the invention is to provide, in a manner as hereinafter set forth, a machine of the class referred to including means operated from the driving mechanism of the machine to provide for an intermittent lifting action for the cocks during the grinding step therefor.

Further objects of the invention are to provide, in a manner as hereinafter set forth, a grinding machine for the purpose referred to which is comparatively simple in its construction and arrangement, strong, durable, compact, thoroughly efficient in its use, providing for uniform production, readily assembled, and comparatively inexpensive to set up and maintain.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of a grinding machine in accordance with this invention.

Figure 2 is a top plan view thereof.

Figure 3 is a section on line 3—3 Figure 2.

Figure 4 is a section on line 4—4 Figure 3. 55

Figure 5 is a section on line 5—5 Figure 1.

Figure 6 is an inverted plan of the lift shaft bearing.

Figure 7 is a sectional elevation of the lift shaft bearing. 60

Figure 8 is an elevation of one of the spindles.

Figure 9 is a top plan view of the lifter assembly.

Figure 10 is a side elevation thereof.

Figure 11 is a sectional plan of the lifter.

Figure 12 is a sectional detail illustrating a keeper.

Figure 13 is a sectional plan of the clutch shifting collar.

Figure 14 is an elevation of a latch.

The machine includes a supporting structure comprising a base 1 preferably constructed of boiler plate. Secured to the plate 1 are two pairs of supporting legs. The legs of each pair are arranged in spaced relation and the legs of one pair are indicated at 2 and the legs of the other pair at 3. The legs 3 are positioned at one end of the base of plate 1 and the legs 2 are arranged at a point removed inwardly with respect to the other end of the base or plate 1. The legs 2, 3 terminate in or secured with a rectangular platform 4, formed with a lengthwise extending chamber 5 corresponding to the length of the platform 4 and opening at one side and at each end of the latter. The top wall of the chamber 5 has the major portion, indicated at 6 positioned above the remaining part thereof as indicated at 7. The bottom wall of the chamber 5 has the major portion thereof, indicated at 8 positioned below the remaining part thereof indicated at 9. The parts 7 and 9 oppose each other, as well as the parts 6 and 8. In transverse section the length of the top and bottom walls of the chamber 5 is such as to extend from the front side to beyond the longitudinal median of the platform 4. 65

The platform 4 is formed with a set of 70

spaced openings 10 and with the set extending lengthwise of the platform. The openings 10 communicate with the chamber 5 through the part 6 of the top wall of the latter. The outer ends of the openings 10 are positioned at the upper face of the platform 4.

The lower part of platform 4 is provided with a set of spaced openings 11 and with the set disposed longitudinally of the platform and with the openings of the set 11 of greater diameter than the openings 10. The openings 11 are arranged below and aligned with the openings 10. The walls of the openings 11 are threaded. The openings 11 communicate with the chamber 5 and extend through the part 8 of the bottom wall of said chamber. The lower face of the platform 4 is provided with spaced bosses 12 through which the openings 11 extend.

The platform 4 between the top and bottom thereof is provided with a longitudinally extending slot 13 which communicates with the chamber 5 and opens at that side of the platform 4 opposite the side in which the chamber 5 opens. The slot 13 is of materially less length than the length of the platform 4 and is positioned centrally of the latter.

Secured to the platform 4, as well as depending therefrom is a plate 13 which closes the outer side of the chamber 5. The plate 13 is detachably secured in position by holdfast devices 14, 15. The ends of the chamber 5 are closed by plates 16 and 17 and which are secured to the platform 4 by suitable holdfast devices 18. The plate 17 is formed with an opening 19 for a purpose to be presently referred to, and said opening aligns with the inner side of the chamber 5 at the rear end thereof. The parts 7 and 9 of the top and bottom walls respectively of the chamber 5 provide guiding means for a reciprocatory element to be presently referred to. Extending from the plate 17 is a guard member 20 for a purpose to be presently referred to.

That side of the platform 4 to which is secured the closure plate 13', is termed the front of the machine.

Mounted on the base or plate 1, adjacent the legs 2, is a prime mover, in the form of a motor 21 having its shaft 22 provided with a pinion 23. Positioned adjacent to and rearwardly of the legs 2 is a stationary guard or gear case 24 for the pinion 23 and also for a gear wheel 25 which meshes with and is driven from the pinion 23. One side of the gear 25 is recessed as at 26 and with the wall 60 of the latter provided at diametrically disposed points with a pair of cam faces 27, 27'. The gear 25 is positioned in proximity to the rear of the platform 4 at that end of the platform supported by the legs 2.

The non-recessed face of the gear 25 has

projecting rearwardly therefrom a crank pin 28 to which is attached a connecting rod 29. The rod 29 is connected at one end to the wrist pin 28 and at its other end connected to a wrist pin 30 carried on the outer end of a laterally disposed arm 31 formed on a reciprocatory rack bar 32 which is positioned between the parts 7 and 9 of the top and bottom walls of the chamber 5 and said parts 7 and 9 provide guides for the rack bar 32. The arm 31 extends outwardly through the slot 13 formed in the platform 4. The function obtained from the rack bar 32 will be presently referred to.

Fixedly secured to the top of the platform 4, at that end of the latter supported by the legs 2, is a bearing 33 for a lift shaft 34. The shaft 34 extends lengthwise with respect to the platform 4 and extends through spaced bearings 35 which are fixedly secured to the top of the platform 4. The shaft 34 has one end thereof extended beyond the bearing 33 and said projecting end, which is indicated at 36 has fixedly secured thereto, by the pin 37, a casting 38 formed with a pin 39, carrying a bearing 40 for a roller 41 which is intermittently engaged by the cam faces 27 and 27' for the purpose of rocking the shaft 34 for moving the lifter assembly to be presently referred to.

The casting 38 projects rearwardly and at right angles from the shaft 34 and extends into the recess 26 so that the pin 39 and the casting 38 will position the roller 41 in the path of the cam faces 27, 27', see Figure 5.

Supported from the platform 4 is a set of grinding mechanisms and the number of the mechanisms of the set corresponds to the number of openings 10 or 11. The openings 10 and 11 are provided for coupling the grinder mechanisms to the platform and said grinder mechanisms extend above and depend below the platform 4. As each of the grinder mechanisms is of the same construction but one will be described, as the description of one will apply to the other.

Each grinder mechanism includes a spindle referred to generally at 42 and it comprises an upper part 43, a pair of intermediate parts 44, 45 and a lower part 46. The spindle 42 is of cylindrical cross section and provided with an axial bore 47 extending from end to end thereof. The upper and the lower portions of the bore 47, indicated at 48, 49 respectively are of greater diameter than the remaining portion of the bore. The walls of the parts 48 and 49 of the bore are threaded. The part 48 is of greater length than the part 49. The parts 43 and 45 of the spindle are of the same diameter and the parts 44 and 46 are also of the same diameter. The part 44 is interposed between the parts 43, 45 of the spindle. The part 43 is of greater length than the part 45 and the part 46 is of greater length than the part 43.

43. The part 44 is of less length than any of the other parts of the spindle. The part 43 at its bottom is formed with a laterally extending, annular flange 50. The part 45 is 5 provided with a radical port 51 which opens into the bore 47. The part 46 is provided with a radical port 52 which opens into the bore 47. The part 46 in proximity to its lower end is formed with a pair of diametrical 10 disposed peripheral lugs 53 which constitute keys for a purpose to be presently referred to.

Secured in the part 49 of the bore 47 and depending from the spindle 42 is a grease cup 15 54. Secured in the part 48 of the bore 47 is a threaded stud 55 for connecting the valve to be ground to the spindle 42.

The spindle 42 is of a length to project a substantial distance above and to depend 20 below the platform 4.

Surrounding the parts 44 and 45 of the spindle 42, below the flange 50, is a bearing sleeve 56 having its upper end provided with a laterally extending annular flange 57 which 25 seats on the upper face of the platform 4. The sleeve 56 is arranged in openings 10 and has its lower edge flush with the part 6 of the top wall of the chamber 5. The part 45 of the spindle 42 depends below the top wall of 30 the chamber 5. The part 44 of the spindle 42 provides what may be termed a grinding clearance. Secured to the threaded wall of an opening 11 is a peripherally threaded bearing 58, having its lower end provided with 35 a laterally extending annular flange 59, which abuts against the boss 12. The upper end of the bearing 58 is beveled to provide a point 59' or rather a sharp corner at the upper end of the inner face of the bearing. Secured to 40 the inner face of the bearing 58 is a bushing 60. The bushing corresponds in length to the bearing and the latter extends a substantial distance above the part 8 of the lower wall of the chamber 5.

45 Loosely mounted on the part 46 of the spindle 42 and supported on the top of the bearing 58 and bushing 60 is a pinion 61 provided with a depending hub 62 of a length to depend below the bearing 58 and bushing 60. The lower end of the hub 62 is formed with 50 clutching teeth 63.

55 Slidably mounted on the lower end of the part 46 of the spindle 42, as well as being connected to the latter by the keys 53 is a clutching member 64 having its top provided with clutching teeth 65 to coact with the teeth 63 for the purpose of clutching the pinion 61 to the spindle 42. The pinion 61 constitutes a driving means for the spindle 42. The member 64 is provided on its periphery with an annular flange 66.

60 Connected to the clutching member 64 is a clutch shifting collar 67 which is constructed in a manner to abut the upper and lower faces of the flange 66 whereby the col-

lar will be permanently carried by the clutching member 64. See Figure 3. With reference to Figure 13 the collar 67 includes a pair of oppositely extending sockets 68 which are diametrically disposed and said collar 67 further includes a detachable ring 69 which removably secures the collar to the clutching member 64.

Pivottally connected with the collar 67 is a shifting yoke therefor consisting of a body portion 70 provided with a pair of arms 71 which are oppositely disposed with respect to each other and which have the collar 67 arranged therebetween. The arms 71 are connected to the collar 67 by pins 72 which engage in the sockets 68. The arms 71 extend inwardly from the body portion 70 and projecting outwardly therefrom is a handle member 73. The plate 13 is formed with a slot 74 to provide a clearance for the handle member 73. The body of the shifting yoke is arranged between a pair of brackets 75 arranged in spaced relation and secured by holdfast devices 76 against the inner face of the plate 13.

Carried by the brackets 75 and extending through the body portion 70 of the shifting yoke is a pivot 77 for the latter. Pivottally connected to the outer face of the plate 13, as at 78 is a depending latch 79 adapted to overlap the handle member 73 for latching it in a position to maintain the clutching member 64 in clutching engagement with the hub 62 whereby the pinion 61 will be coupled to the spindle 42 and the latter will be driven from said pinion.

The pinion 61 is driven from the reciprocating rack bar 32 and meshes therewith. The rack bar is of a length to permanently mesh with the pinions 61 of the grinding mechanisms. When the pinions 61 of the grinding mechanisms are clutched to the spindles 42 of such mechanism, these latter will be simultaneously operated, but the clutching means permit of selectively discontinuing the operation of a grinding mechanism when desired.

Mounted on the top of each spindle 42 is a hollow frusto-conical combined mechanism protector and drip deflecting member 78' through which extends the stud 55. Mounted on the stud 55 is a clamping nut 79' which bears against the top of the member 78' for fixedly securing it in position with respect to the spindle 42. The member 79' at its lower end is of greater diameter than the flanges 50 and 57.

Positioned on the top of the platform 6 is a drip pan 79'' provided with vertically disposed annular collars 80 for surrounding the abutting flanges 50 and 57. The collars 80 project above the flanges 50. The members 78' extend over the tops of the collars 80 and into the pan 79''. The sides and ends of the

pan 79" are of greater height than the height of the collars 80.

Associated with each grinding mechanism is a lifter assembly and the said assemblies are carried by the lifter shaft 34. Each assembly comprises a V member or casting 81 having the arms thereof designated at 82 and each of which is formed with an opening 83 for the passage of the shaft 34. Holdfast means 84 are provided for securing the arms 82 to the shaft 34. Extending through the body portion 85 of the V member 81, as well as threadedly engaging therewith is an adjusting screw 86. Carried by the body portion 85 is a keeper 87 for the screw 86. Loosely mounted on the shaft 34 between the arms 82 of the V member 81 is a lifter member consisting of a stem 88 having a downturned inner portion 89. The stem 88 is formed with an opening 90 for the passage of the shaft 34. Formed integral with the outer end of the stem 88 is a pair of oppositely extending curved arms 91, 92 having upstanding enlargements 93 on the upper face of each arm at the inner end thereof. The downturned portion 89 of the stem 88 is positioned in the path of the adjusting screw 86, which also acts as a means for rocking the lifting member on the shaft 34 to lift the valve housing or body. The length of the lift can be governed by the adjusting of the screw 86. The arms 91, 92 of the lifting member straddle the stud 55, as well as being spaced therefrom and in this connection see Figure 2.

Connected to the top of the platform 4, upon the front thereof, is a series of stops or holders for the valve housing or body. The end holders of the set are indicated at 94, 95 and are of inverted L-shape and oppositely disposed with respect to each other. The intermediate holders of the set are indicated at 96 and are of T-shape form. Each holder 96 opposes and is spaced from a bearing 35 as well as extends above the same. An end holder 95 is positioned to oppose a bearing 35 as well as being spaced therefrom and extending above the bearing. The end holder 94 is arranged in opposed relation with respect to the shaft 34 and extends above the same.

The holders are vertically disposed, are arranged in spaced relation and are also spaced from the grinding mechanisms and lifter assemblies.

The bore 47 and ports 51, 52 provide lubricant channels. The pinions 61 are turned to an angle slightly greater than 360° then reversed and turned in the opposite direction.

The construction of the bearings 33 and 35 is best shown in Figure 7 and which consists of a base 97, a shank 98, a tubular head 99, a bushing 100 within the head and an oil hole 101. The base 97 has openings 102 for the passage of holdfast devices 103 to fixedly secure the bearing to the platform 4.

The stops or holders 94, 95, 96 are threaded into the platform 4 and carry holding nuts 104. The pan 79" is common to the said several members 78' and has inset portions 105 for the nuts 104. See Figure 2. The pan 79" is furthermore provided with openings 106 for the passage of the grinder mechanisms. The collars 80 are flush with the edges of the openings 106. The latches 79 are pivoted on the enlarged cylindrical parts 107 of the shanks of the holdfast devices 15. See Figure 3. The plate 16 has a grease cup 108 attached thereto which opens into the inner side of the journal 25' of the gear 25. Oil holes 109 are provided for the ends of the connecting rod 29. A dust collar 110 is mounted on pin 39 and between the latter and casting 38. See Figure 5.

In operation, power is applied to the gear wheel 25 causing it to rotate and impart a reciprocatory motion to the rack bar 32 and as the latter meshes with the pinions 61 these latter are turned through an angle slightly greater than 360° and then reversed and turned in the opposite direction as the rack bar reciprocates. By means of the clutches the toothed ends of the hubs of the pinions 61 are engaged and cause the spindles to rotate as an integral part of the pinions. It is evident then that by engaging or disengaging the clutches each spindle may be operated independently of the others, and started or stopped at the will of the operator.

At each half of a revolution of the gear 25 the cam surfaces 27 and 27' pass over roller 41, depressing it and causing the forked end of lifter to be raised, striking the valve body or housing and raising it from the valve. This admits grinding compound or abrasive material and oil into the valve and also prevents grinding grooves or irregular depressions in the valve parts. The amount of lift given the valve body or housing by the lifters is governed by the set screws 86 and is individually adjustable for each valve. The valve body is prevented from rotating with the valve by means of the holders or stops 94, 95 and 96.

It is thought the many advantages of a grinding machine for the purpose set forth can be readily understood, and although the preferred embodiment of the invention is as illustrated and described, yet it is to be understood that changes in the details of construction can be had which fall within the scope of the invention as claimed.

What we claim is:

1. In a grinding machine for the purpose set forth, the combination of a plurality of vertically disposed work grinding mechanisms each including a driving pinion therefor above the lower end thereof, a reciprocatory element common to said pinions for operating them, a driven gear carrying a crank pin on one side and having its other

side provided with cam surfaces, a driving connection between said pin and element, a lifter assembly associated with each mechanism for lifting the work relative to the latter during the grinding action, a lifter shaft common to said assemblies for actuating them simultaneously to lift the work relative to said grinding mechanisms, and means extending from one end of said shaft and successively engaged by said cam faces for intermittently rocking said shaft to provide for the intermittent actuation of said assemblies.

2. In a grinding machine for the purpose set forth, the combination of a plurality of vertically disposed work grinding mechanisms each including a driving pinion therefor above the lower end thereof, a reciprocatory element common to said pinions for operating them, a driven gear carrying a crank pin on one side and having its other side provided with cam surfaces, a driving connection between said pin and element, a lifter assembly associated with each mechanism for lifting the work, relative to the latter during the grinding action, a lifter shaft common to said assemblies for actuating them simultaneously to lift the work relative to said grinding mechanisms, means extending from one end of said shaft and successively engaged by said cam faces for intermittently rocking said shaft to provide for the intermittent actuation of said assemblies, each of said assemblies including means for controlling the extent of the lifting action thereof with respect to the work.

3. In a grinding machine for the purpose set forth, the combination of a plurality of vertically disposed work grinding mechanisms each including a driving pinion therefor above the lower end thereof, a reciprocatory element common to said pinions for operating them, a driven gear carrying a crank pin on one side and having its other side provided with cam surfaces, a driving connection between said pin and element, a lifter assembly associated with each mechanism for lifting the work relative to the latter during the grinding action, a lifter shaft common to said assemblies for actuating them simultaneously to lift the work relative to said grinding mechanisms, means extending from one end of said shaft and successively engaged by said cam faces for intermittently rocking said shaft to provide for the intermittent actuation of said assemblies, and means to provide for selectively discontinuing the operation of said grinding mechanisms from the driving pinions thereof.

4. In a grinding machine for the purpose set forth, the combination of a plurality of vertically disposed work grinding mechanisms each including a driving pinion therefor above the lower end thereof, a reciprocatory element common to said pinions for

operating them, a driven gear carrying a crank pin on one side and having its other side provided with cam surfaces, a driving connection between said pin and element, a lifter assembly associated with each mechanism for lifting the work relative to the latter during the grinding action, a lifter shaft common to said assemblies for actuating them simultaneously to lift the work relative to said grinding mechanisms, said means extending from one end of said shaft and successively engaged by said cam faces for intermittently rocking said shaft to provide for the intermittent actuation of said assemblies, each of said assemblies including means for controlling the extent of the lifting action thereof with respect to the work, and means to provide for selectively discontinuing the operation of said grinding mechanisms from the driving pistons thereof.

5. In a grinding machine, a rotatable grinding mechanism including a driving pinion therefor, a lifter assembly for lifting the work relative to the grinding mechanism during the grinding action, said lifter assembly including a loosely mounted lifter arm and a combined adjusting and shifting means for said arm, a rock shaft common to said arm and shifting means and having the latter fixed thereto, a reciprocatory rack bar for operating said pinion, a lever arm for operating said rock shaft, said arm carried by the rock shaft, and a rotatable element common to said rack bar and lever arm for continuously operating the former and intermittently operating the latter to provide for the intermittent operation of the rock shaft.

6. In a grinding machine, a rotatable grinding mechanism including a driving pinion therefor, said driving pinion being normally and loosely mounted relative to the other elements of the grinding mechanism, a lifter assembly associated with said mechanism for lifting the work relative thereto during the grinding action on the work, said lifter assembly including a loosely mounted lifter arm and a combined adjusting and shifting means for said arm, a rock shaft common to said arm and shifting means and having the latter fixed thereto, a reciprocatory rack bar for operating said pinion, means for coupling the pinion in driving position with respect to said grinding mechanism to provide for the operation thereof, a lever arm carried by and operating said rock shaft, and a rotatable element common to said rack bar and lever arm for continuously operating the former and intermittently operating the latter to provide respectively for the operation of the pinion and the intermittent operation of the rock shaft.

7. In a grinding machine, a rotatable grinding mechanism for the work, said mechanism including a driving pinion therefor, a lifter assembly associated with said

mechanism for lifting the work relative thereto during the grinding action on the work, said lifter assembly including a loosely mounted lifter arm and a combined adjusting and shifting means for said arm, a rock shaft common to said arm and shifting means and having the latter fixed thereto, a reciprocatory rack bar for operating said pinion, a lever arm carried by said rock shaft and provided with a roller, and a rotatable element common to said rack bar and said roller for continuously operating the former and intermittently shifting the latter to provide respectively for the operation of said rack bar and the intermittent operation of said rock shaft.

8. In a grinding machine for the purpose set forth, a supporting structure, a plurality of spaced, vertically disposed work grinding mechanisms supported by and extending above said structure, each of said mechanisms including a grinding pinion therefor, a reciprocatory element slidably mounted in said structure and common to said pinions for operating them, said element provided intermediate its ends with an arm projecting outwardly from said structure, a combined gear and cam positioned adjacent one end of said structure, an operative drive connection between said combined gear and cam and said arm to provide for the reciprocation of said element, a lifter assembly mounted on said structure and associated with each grinding mechanism and providing for lifting the work relative to the mechanism during the grinding action on the work, a lifter shaft supported over said structure and common to said assemblies for actuating them simultaneously, means carried by one end of said shaft and intermittently operated from said combined gear and cam for intermittently rocking said shaft to provide for the actuation of said assemblies, and means for selectively controlling the operation of said grinding mechanisms.

9. In a grinding machine for the purpose set forth, a supporting structure, a plurality of spaced, vertically disposed work grinding mechanisms supported by and extending above said structure, each of said mechanisms including a grinding pinion therefor, a reciprocatory element slidably mounted in said structure and common to said pinions for operating them, said element provided intermediate its ends with an arm projecting outwardly from said structure, a combined gear and cam positioned adjacent one end of said structure, an operative drive connection between said combined gear and cam and said arm to provide for the reciprocation of said element, a lifter assembly mounted on said structure and associated with each grinding mechanism and providing for lifting the work relative to the mechanism during the grinding action on the work, a lifter

shaft supported over said structure and common to said assemblies for actuating them simultaneously, means carried by one end of said shaft and intermittently operated from said combined gear and cam for intermittently rocking said shaft to provide for the actuation of said assemblies, means for selectively controlling the operation of said grinding mechanisms, a combined protector and drip directing member connected to and depending from the upper end of each of said grinding mechanisms, surrounding said mechanisms and spaced from said assemblies, and a collector seated on said structure, common to and having said grinding mechanisms extending therethrough and further having said members extending into and discharging therein.

10. A grinding machine for the purpose set forth, the combination of a supporting structure, a plurality of spaced, vertically disposed grinding mechanisms supported by and extending above such structure, each of said mechanisms including a driving pinion therefor above the lower end thereof, a reciprocatory element slidably mounted in said structure and common to said pinions for operating them, said element provided intermediate its ends with an arm projecting outwardly from said structure, a driven combined gear and cam positioned adjacent one end of said structure, a driving connection between said combined gear and cam and said arm to provide for the reciprocation of said element, lifter assemblies mounted on said structure and each associated with a grinding mechanism thus providing for lifting the work being acted upon during the grinding action on the work, a lifter shaft supported over said structure and common to said assemblies for actuating them simultaneously, means projecting from one end of said shaft and intermittently engaged by said combined gear and cam for intermittently rocking said shaft to provide for the actuation of said assemblies, and each of said assemblies including means for controlling the extent of its movement.

11. A grinding machine for the purpose set forth, the combination of a supporting structure, a plurality of spaced, vertically disposed grinding mechanism supported by and extending above such structure, each of said mechanisms including a driving pinion therefor above the lower end thereof, a reciprocatory element slidably mounted in said structure and common to said pinions for operating them, said element provided intermediate its ends with an arm projecting outwardly from said structure, a driven combined gear and cam positioned adjacent one end of said structure, a driving connection between said combined gear and cam and said arm to provide for the reciprocation of said element, lifter assemblies mounted on

said structure and each associated with a grinding mechanism thus providing for lifting the work being acted upon during the grinding action on the work, a lifter shaft supported over said structure and common to said assemblies for actuating them simultaneously, means projecting from one end of said shaft and intermittently engaged by said combined gear and cam for intermittently 5 rocking said shaft to provide for the actuation of said assemblies, each of said assemblies including means for controlling the extent of its movement, and means for selectively controlling the operation of said grinding mechanisms.

In testimony whereof, we affix our signatures hereto.
